UNITED STATES PATENT OFFICE.

WALLACE WARD MALLEY, OF NEW HAVEN, CONNECTICUT.

DESIGN FOR A BENCH.

Application filed August 14, 1924. Serial No. 10,458. Term of patent 7 years.

To all whom it may concern:

Be it known that I, WALLACE WARD MALLEY, a citizen of the United States, residing at New Haven, in the county of New Haven and State of Connecticut, have invented a new, original, and ornamental Design for Benches, of which the following is a specification, reference being had to the accompanying drawings, forming part thereof.

The figure is a perspective view of a bench showing my new design.

I claim:

The ornamental design for a bench as shown.

WALLACE WARD MALLEY,
V. Pres. The Edw. Malley Co.
